UNITED STATES PATENT OFFICE.

LEWIS G. REYNOLDS, OF DAYTON, OHIO.

MANIFOLDING SALES-BOOK.

SPECIFICATION forming part of Letters Patent No. 655,456, dated August 7, 1900.

Application filed January 11, 1900. Serial No. 1,122. (No model.)

To all whom it may concern:

Be it known that I, LEWIS G. REYNOLDS, a citizen of the United States, residing at Dayton, in the county of Montgomery and State 5 of Ohio, have invented certain new and useful Improvements in Memorandum Sales-Slip Books, of which the following is a full, clear, and exact description, reference being had to the accompanying drawings, forming part of 10 this specification.

My improvement relates to sales-slip books for use in making duplicate memoranda of sales and the like for use by merchants and others, and the improvements have particular 15 relation to that class of sales-slip book known as "flat-opening." In sales-slip books belonging to the flat-opening class the sheets are bound together at one end and are provided with two lines of perforations—one at the 20 bound end to form a stub and the other at the middle of the sheet to allow for the ready separation of the individual sheet from the package and the two portions of the sheet from each other. In the flat-opening sales-slip 25 books the sheets lie in contact with each other throughout their whole length, and a sheet of carbon-paper of a length to cover the sheet to the middle line of perforations is bound with the package on top of the sheets. In this construction of book the free ends of the sheets—that is, that portion from the middle line of 30 perforations outward—lie in contact with each other, and these portions of the sheets become the original slips, while those portions 35 attached to the stub become the duplicate slips. When this class of book is folded and closed, the fold is made at the middle line of perforation, the original slips all lying in contact with each other. (This type of flat-opening book, in which the sheets lie in contact 40 with each other, is well exemplified in the patent of J. H. Frink, No. 288,048, of November 6, 1883.) In another type of sales-slip book of this class and which could be called 45 the "folded-in" style of book the individual sheets are folded each original slip upon its corresponding duplicate, and this type of folded-in book as distinguished from the flat-opening book is well exemplified in the patent to Oldfield, No. 485,132, of October 25, 1892.

My improvements relate to the flat-opening book, as above described, in which the sheets

lie in contact with each other throughout their whole length, and the phrase "lying in contact with each other" as used hereinafter 55 in this specification and the claims is intended to refer to the Frink patent style of flat-opening book as distinguished from the Oldfield patent style, where the sheets are folded each original upon its corresponding duplicate slip. In the flat-opening book as the slips are to be written in the hurry of a sale the salesman is very apt to turn over more than one slip at a time, or in any event the recording 60 of a sale is delayed while the salesman selects the top slip to be folded over the carbon-paper. In sales-slip books of this class it has also been customary to provide a sales-entry sheet for the recording of the sales-memoranda made on the slips, and this sales-entry sheet 65 has been placed within the back cover of the book, so that in order to record the sales the unused slips which lie together within the back cover have to be lifted out of the way, so as to expose the sales-entry sheet, thus for 70 the moment concealing the original sales-slip just used and affording an opportunity for error in the posting of the data of the sale on the sales-entry sheet. It is to overcome these various features of objection to the use 75 of sales-slip books in which the sheets lie in contact with each other that my invention is directed, and it consists in providing the cover of the book with an extra fly-leaf section approximately the same length as the so-called "original" slip, which is adapted to 80 fold over the free ends of the original sales-slips, forming a receptacle therefor and covering the unused portion of the sales-slips while the book is being used and to separate 85 the next-to-be-used slip from the balance of the slips. The sales-entry columns are imprinted on the top side of this extra section of the cover, which brings the line and point of record directly under the original sales-memoranda on the sales-slip in plain view of the writer, doing away with the liability of 90 error in the posting, and in addition to this the extra fly-leaf cover-section furnishes a means for separating the next slip to be used 95 from the balance of the sheets, so that the book is ready for instant use for the next sale. In order to maintain this extra fly-leaf cover-section in a position to form a recepta- 100

- cle for the outer ends of the sales-slips, I preferably make use of a clip which embraces the fold of the fly-leaf cover-section and keeps it constantly folded at the outer end.
- 5 In separating the slip next to be used from the balance of the sheets the salesman lifts the fly-leaf cover-section and slides the uppermost slip from the others, but the clip prevents access to the ends of the slips, and 10 there is much less likelihood of turning over more than one slip at a time.
- In the drawings, Figure 1 is a perspective view of my improved book open and ready for use. Fig. 2 is a side elevation of the book closed.
- 15 The sheets of paper forming the book are provided with two lines of perforations *a b*, leaving a stub portion A, duplicate slips B, and original slips C.
- 20 D is the cover for the book, made of Manila paper or other suitable material and provided with an upper fly-leaf E and a lower cover-section fly-leaf F. The upper fly-leaf E is carbonized to form manifolding material, or instead of carbonizing this fly-leaf the fly-leaf may be omitted and a separate sheet of manifolding material may be secured to the stub portion of the sheets in any well-known way. The lower fly-leaf cover-section 25
- 25 F is imprinted on its outer side with a form for a sales-entry sheet upon which to post the sales. The sheets of paper and the cover are bound together through the stub portion of the sheets by staples *cc* or otherwise suitably
- 30 F is imprinted on its outer side with a form for a sales-entry sheet upon which to post the sales. The sheets of paper and the cover are bound together through the stub portion of the sheets by staples *cc* or otherwise suitably
- 35 blocked or secured together and the book is ready for use, the lower cover-section being folded over all of the slips except the topmost, and this slip being folded over the manifolding material.
- 40 When the sales-memoranda have been made on the original slip, the total is at once posted on the sales-entry sheet, which lies directly before the salesman, so that error in posting is avoided. The original and duplicate slips 45 are then torn out on the upper line of perforation *a*, and the slips separated, as is usual. Having made the record and detached the slips, the salesman folds over the original of the next slip upon the carbon material
- 50 and folds the book, as shown in Fig. 2. This operation of folding over the next-to-be-used slip is performed at a moment when in the regular course of business the clerk or salesman has time to do it, is not in a hurry, and 55 therefore not liable to make an error by folding over two or more instead of only one. The cover-section F then separates the topmost or next-to-be-used slip from the others, and the book is ready for instant use when
- 60 next opened. To maintain this cover-section F firmly as a receptacle, I preferably make use of a clip *g*, of tin or other suitable material, which is bent around the outer fold of the cover-section F and the back D and 65 held in that position by its own spring-pressure. This insures the position of the cover-section F, and when it is raised to obtain the

slip next to be used the natural spring of the material prevents access to the outer ends of the slips.

Having thus described my invention, what I claim, and desire to secure by Letters Patent, is—

1. A memorandum sales-slip book composed of the series of sheets of paper perforated at the middle to form duplicate and original slips, said sheets lying in contact with each other throughout their whole length, provided with a cover of suitable material having a fly-leaf cover-section, approximately of the same length as the original-slip portion of the sheet, folded over the free ends of the original slips, whereby the next-to-be-used original slips may be separated from the balance of the original slips, substantially as shown and described. 80

2. A memorandum sales-slip book, composed of a series of sheets of paper, perforated at the middle to form duplicate and original slips, said sheets lying in contact with each other throughout their whole length, provided with a cover of suitable material, having a fly-leaf cover-section, approximately of the same length as the original-slip portion of the sheets, folded over the free ends of the original slips and imprinted on its outer side with proper matter to serve as a sales-entry sheet for posting a summary of the sales, whereby the next-to-be-used original slip may be separated from the balance of the original slips, substantially as shown and described. 90

3. A memorandum sales-slip book, composed of a series of sheets of paper perforated at the middle to form duplicate and original slips and lying in contact with each other, provided with a cover of suitable material, having a fly-leaf cover-section approximately of the same length as the original section, folded over the free ends of the original slips, whereby the next-to-be-used slip may be separated from the balance of the original slips, and means for maintaining the fly-leaf cover-section in folded position, substantially as shown and described. 100

4. A memorandum sales-slip book, composed of a series of sheets of paper perforated at the middle and lying in contact with each other, provided with a cover of suitable material, having a fly-leaf cover-section, approximately of the same length as the original section, folded over the free ends of the original slips, forming a cover for the original slips not ready for use, and serving as a means for separating the next-to-be-used slip from the balance of the original slips, said fly-leaf cover-section serving as a sales-entry sheet for posting a summary of sales, and a clip for maintaining said fly-leaf cover-section in folded position, substantially as shown and described. 110
